Primary Examiner — Melanie H Tung*Assistant Examiner* — Darmawan Truong(74) *Attorney, Agent, or Firm* — Crestron Electronics, Inc.(57) **CLAIM**

The ornamental design for an electronic device with icon, as shown and described.

DESCRIPTION

FIG. 1 is a front view of a first embodiment of an electronic device with icon; and,

FIG. 2 is a second embodiment thereof.

The broken lines showing the electronic device in FIG. 1 and an alternate electronic device in FIG. 2 forms no part of the claimed design. The remaining broken lines showing portions of the icon form no part of the claimed design.

1 Claim, 2 Drawing Sheets(56)
